UNITED STATES PATENT OFFICE.

EPPA H. RYON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

BRAKE MECHANISM FOR LOOMS.

SPECIFICATION forming part of Letters Patent No. 789,388, dated May 9, 1905.

Application filed March 9, 1904. Serial No. 197,231.

To all whom it may concern:

Be it known that I, EPPA H. RYON, a citizen of the United States, residing at Worcester, in the county of Worcester and State of

5 Massachusetts, have invented certain new and useful Improvements in Brake Mechanism for Looms, of which the following is a specification.

10 My invention relates to a brake mechanism for a loom, and more particularly to an improved construction of the brake mechanism ordinarily used to brake or stop the crank-shaft on the movement of the brake-lever on the stopping of the loom.

15 The object of my invention is to provide an improved brake mechanism of simple construction and effective in operation; and my invention consists in certain novel features of construction of my improvements, as will be 20 hereinafter fully described.

25 Referring to the drawings, Figure 1 is a side view of a portion of a loom-frame with my improvements applied thereto. Fig. 2 corresponds to Fig. 1, but shows some of the parts of 30 the mechanism in their opposite position; and Fig. 3 is, on an enlarged scale, a perspective view of the brake-lever and shipper-lever and some of the other parts shown in Fig. 1.

35 In the accompanying drawings, 1 is the 30 loom-frame.

2 is the crank-shaft, journaled in bearings 3 on the frame 1. Fast on the crank-shaft is the brake-wheel 4, shown by broken lines. The friction-band 5 for the brake-wheel 4 is 35 pivoted at one end on a stud 6 on the loom-frame 1 and is bent around the wheel 4, as shown, and attached to a rod 7, which has a threaded end 7', which extends loosely through a boss 8' on a lever 8, which is pivoted on a 40 stub 9 on the frame 1. On the threaded end 7' of the rod 7 are two nuts 9' to hold the rod 7 in the boss 8' and allow of the adjustment of said rod.

45 A spring 10 is attached at one end to the frame 1 and at its other end to the lever 8. The spring 10 acts to hold the band 5 in its inoperative position, as shown in Fig. 1, when the loom is in operation; but on the backward

movement of the brake-lever, to be herein-after described, on the stopping of the loom 50 the spring 10 acts to draw the band 5 down on the wheel 4 and apply the friction.

On the upper end of the lever 8 is a boss 8", through which extends loosely the threaded end 11' of a connector or rod 11. A nut 11" 55 on the threaded end 11' of the rod 11 holds the end 11' in the boss 8" and allows of the longitudinal adjustment of the rod 11. The other end of the rod 11 is pivotally attached to an arm 12' on the hub 12" of the brake-lever 12. The hub 12" is loosely mounted on a stud 13 on the loom-frame 1.

The brake-lever 12 extends up above the breast-beam 14, as is customary, and extending out from the lever 12 is an arm 12", carrying a pin 16, on which is pivotally mounted a pawl 17, one end, 17', of which extends under and is engaged by a pin 18 on a projection 19' on the shipper-lever 19, mounted on the stud 13. Thus the end 17' of the pawl 17 is held 70 out of engagement with the knock-off lever 20 when the loom is turned over by hand, and the brake will not be applied should the dagger come in contact with the knock-off lever 20 at such a time. The other end, 17", 75 of the pawl 17 is heavier than the end 17' and is adapted in its lowered position to be engaged by the knock-off lever 20 when the shipper-lever is in its forward position and the loom is in operation. A pin 20' on the 80 brake-lever 12 limits the upward motion of the end 17" of the pawl 17. (See Fig. 2.)

On the brake-lever 12 is an extension 21, the end 21' of which is in this instance adapted to engage the loom-frame (see Fig. 3) and 85 limit the forward motion of the lever 12. The end 21" of the extension 21 is adapted to engage a projection 19" on the shipper-lever 19.

The brake-lever 12 is held in its normal position by the spring 10 through the pivot-point of the connector-rod 11 to the arm 12' on the lever 12 being above the dead-center, as shown in Fig. 1. The pivotal point between the rod 11 and the arm 12' on the brake-lever 12 is so located that by a slight move-

ment thereof the spring 10 of the brake mechanism is enabled to release or to apply the brake-band 5 on the brake-wheel 4.

On the upper side of the breast-beam is 5 shown the filling stop-motion lever 22. (See Fig. 3.)

When the loom is to be started, the shipper-lever 19 is moved or drawn forward in the usual way. The movement of the pin 18 10 on the lever 19 with said lever allows the end 17" of the pawl 17 to drop into the path of the knock-off lever 20. In case it is desired to stop the loom suddenly the inward movement of the brake-lever 12 in the direction of 15 the arrow *b*, Fig. 3, will, through the engagement of the projection 21 on said lever with the projection 19" on the shipper-lever 19, move said lever 19 and stop the loom and through connections from the brake-lever si- 20 multaneously apply the brake-band 5 to the brake-wheel 4. The automatic movement of the knock-off lever 20, engaging the end 17" of the pawl 17, carried on the brake-lever 12, will move said lever 12 and the shipper-lever 25 19 and stop the loom and operate the brake mechanism.

The shipper-lever 19 can be operated independently of the brake-lever 12 to stop the loom if it is desired to turn the loom by hand; 30 but the brake-lever 12 cannot be operated to stop the loom without operating the shipper-lever.

In case the brake-lever 12 is in its rear position, as shown in Fig. 2 of the drawings, 35 and the friction-band 5 applying friction on the brake-wheel 4, the forward movement of the shipper-lever 19 to start the loom will, through the engagement of the projection 19" thereon with the end 21" of the arm 21 on 40 the brake-lever 12, move forward the brake-lever 12 and release the friction of the band 5 on the brake-wheel 4.

It will be understood that the details of construction of my improvements may be varied 45 if desired.

Having thus described my invention, what I claim as new, and desire to secure by Letters Patent, is—

1. In a brake mechanism of a loom, a brake-wheel, a friction-band therefor connected with 50 a pivoted lever, and said pivoted lever, a spring connected therewith, a connection from said lever to a brake-lever, and said brake-lever carrying a pawl to engage the knock-off lever, and said knock-off lever and said brake- 55 lever having a projection to engage the shipper-lever, and said shipper-lever carrying a pin to engage said pawl, the operation of the brake-lever to apply the brake causing the operation of the shipper-lever to stop the 60 loom, substantially as shown and described.

2. In a brake mechanism of a loom, the combination with a brake-wheel, a friction-band therefor, intermediate connections between said friction-band and a brake-lever, and said 65 brake-lever carrying a pawl to be engaged by the knock-off lever, and said knock-off lever, of the shipper-lever, adapted to be engaged by the brake-lever, and to be operated to stop the loom on the operation of the brake-lever 70 and through intermediate connections to operate the friction-band to apply friction to the brake-wheel, substantially as shown and described.

3. In a brake mechanism, a brake-lever piv- 75 otally supported, an arm on said lever, a friction device pivotally connected with said arm, a spring connected with said friction device, and acting to hold the pivotal point of said connection and said arm substantially in line 80 with the pivot-support of said arm, to hold the friction device in its inoperative position, and on the backward movement of said brake-lever said spring acting to apply the friction, substantially as shown and described.

EPPA H. RYON.
